ATTORNEYS

UNITED STATES PATENT OFFICE.

JOHN O'CONNOR, OF NEW YORK, N. Y.

SOFT-COLLAR HOLDER.

1,369,703.

Specification of Letters Patent. Patented Feb. 22, 1921.

Application filed September 16, 1920. Serial No. 410,653.

To all whom it may concern:

Be it known that I, JOHN O'CONNOR, a citizen of the United States, and a resident of the city of New York, borough of Manhattan, in the county and State of New York, have invented a new and Improved Soft-Collar Holder, of which the following is a full, clear, and exact description.

Devices for holding soft collars in a manner to maintain the collar in proper set, are adapted to engage the collar within the same at the juncture of the band and outer portion or collar proper and are provided with means to engage the collar button as well as with means to engage the flaps of the collar. Devices for the purpose have also been formed of an upper collar engaging section and a lower button engaging section, the two sections being vertically adjustable for varying the total height of the holder to suit different sizes or shapes of collars. In the case of the vertically adjustable holders the means for engaging the collar flaps has been provided on the upper collar engaging section and therefore when the upper and lower sections are adjusted the relative positions of the flap engaging means and the button engaging means have been changed so that the flap engaging means are not properly positioned when the collar engaging member is raised a material distance.

The general object of my invention is to provide a soft collar holder comprising upper and lower sections adjustably connected and at the same time to provide flap engaging means and button engaging means in fixed relative positions and unaffected by the adjustment of the sections.

Reference is to be had to the accompanying drawings forming a part of this specification, it being understood that the drawings are merely illustrative of practical examples of the invention.

Figure 1 is a front elevation of a soft collar holder embodying my invention in one form and showing the same in use, a collar being shown in perspective.

Fig. 2 is an enlarged front elevation of said holder.

Fig. 3 is a horizontal section on the line 3—3 of Fig. 2.

Fig. 3^a is a detail in horizontal section, and on an enlarged scale as indicated by the line 3^a—3^a of Fig. 2.

Fig. 4 is a view similar to Fig. 2, but showing the invention in another form.

Fig. 5 is a horizontal section on the line 5—5 of Fig. 4.

Referring first more particularly to Figs. 1 to 3^a, my improved soft collar holder comprises an upper section 10 and a separate lower section 11. Said upper section has a suitable formation for supporting engagement with the collar A, there being shown upwardly inclined wings 12 thereon at opposite sides. The upper section 10 includes a vertical shank 13 having a vertical slot 14 therein. The shank of a fastening screw 15 passes through the slot 14 and has threaded engagement with the vertical shank 17 on the lower section 11 on which the shank 13 is slidable between longitudinal edge flanges 16.

The lower section 11 is provided with means to engage a collar button indicated at B, Fig. 1, there being shown for the purpose a vertical slot 18 accommodating the shank of the collar button, and I provide also on said button engaging section 11 means to engage the collar flaps adjacent to the corners. In Figs. 1 to 3^a the section 11 is formed with oppositely extending lateral arms 19 at the sides on which clamp plates 24 are provided for clamping the collar material against the arms 19. The arms 19 are adapted to extend at their ends beneath the under side of the collar, while the clamps 20 lie at the front of the collar and may have any suitable design. The clamps 20 in the example shown have rearwardly bent arms 90 at their inner ends which extend through openings 19^a in the arms 19 to the back of said arms and are engaged by plate springs 21 secured in any suitable manner to said arms 19 at the back. The arrangement is 95 such that the clamps may be normally closed by the springs against the arms 19. The clamps 20 are hinged to the arms 19 at the openings 19^a, as indicated at 23. Advantageously the arms 19 have forwardly extending toothed gripping projections 24 on the front faces thereof beneath the clamps 20 so that the material of the collar is effectively held between said clamps and projections.

With the described arrangement it will be observed that the adjustment of the shanks 13 and 17 through the medium of the screw 15 will not alter the relative positions of the clamps 20 and the button engaging slot 18, since both of these are in fixed relative positions on the lower section 11 of the

holder, and therefore the clamps for the collar flaps will always be maintained in proper position irrespective of the adjusted height of the holder.

5 In the form shown in Figs. 4 and 5 the upper slotted section 10 as well as the shank 17 of the lower section and the adjusting screw 15 are the same as in Figs. 1 to 3^a. Instead, however, of employing clamps for 10 the collar flaps I provide on the arms 19^b, corresponding generally with the arms 19, pointed terminal ends or spurs 19^c which are return-bent to be disposed laterally inward at the front of said arms 19^b in position to penetrate the material of the collar flaps near the corners.

I would state in conclusion that while the illustrated examples constitute practical embodiments of my invention, I do not limit 20 myself strictly to the mechanical details herein illustrated, since manifestly the same can be considerably varied without departure from the spirit of the invention as defined in the appended claims.

25 I claim:

1. A holder for soft collars including an upper section adapted to have supporting engagement with the collar within the latter, a lower section having means at its 30 lower end to engage a collar button, means to adjustably connect said upper and lower sections to vary the total height of the

holder, and collar-flap-engaging means carried by said lower section at the sides thereof near the lower end, said button engaging 35 means and said flap engaging means being in fixed relative positions on said lower section so that their relative positions are unaltered by the adjustment of said upper and lower sections.

2. A holder for soft collars including an upper section adapted to have supporting engagement with the collar within the latter, a lower section having means at its lower end to engage a collar button, means 40 to adjustably connect said upper and lower sections to vary the total height of the holder, lateral arms extending in opposite directions on said lower section at opposite sides of the button engaging means, and means on said 45 arms to engage the flaps of a collar.

3. A holder for soft collars including an upper section adapted to have supporting engagement with the collar within the latter, a lower section having means at its lower 55 end to engage a collar button, means to adjustably connect said upper and lower sections to vary the total height of the holder, lateral arms extending in opposite directions on said lower section, and clamps on 60 said arms adapted to engage the flaps of a collar.

JOHN O'CONNOR.
